ARC LAMP.

900,718.

APPLICATION FILED MAY 1, 1905.

Patented Oct. 13, 1908.

2 SHEETS—SHEET 2.

UNITED STATES PATENT OFFICE.

RICHARD FLEMING AND CROMWELL A. B. HALVORSON, JR., OF LYNN, MASSACHUSETTS,
ASSIGNORS TO GENERAL ELECTRIC COMPANY, A CORPORATION OF NEW YORK.

ARC-LAMP.

No. 900,718.

Specification of Letters Patent. Patented Oct. 13, 1908.

Application filed May 1, 1905. Serial No. 258,214.

To all whom it may concern:

Be it known that we, RICHARD FLEMING and CROMWELL A. B. HALVORSON, Jr., citizens of the United States, residing at Lynn, 5 in the county of Essex and State of Massachusetts, have invented certain new and useful Improvements in Arc-Lamps, of which the following is a specification.

Our present invention relates to arc lamps, 10 and more particularly to arc lamps of the type in which the electrodes employed are such that flaming or luminous arcs are obtained which furnish the major portion of the light given by the lamps.

15 Our present invention is shown as embodied in a lamp structure which is a modification of that shown in our application Serial No. 181,332, filed November 16, 1903.

The various features of novelty which 20 characterize our invention are pointed out with particularity in the claims annexed to and forming a part of this specification.

For a better understanding of our invention, however, reference may be had to the 25 accompanying drawings and descriptive matter in which we have illustrated and described forms in which our invention may be embodied.

Of the drawings, Figure 1 is a perspective 30 view of an arc lamp with the casing and globe removed; Fig. 2 is an elevation with parts in section and broken away showing the circuit controlling means of the lamp; Fig. 3 is a diagrammatic representation of 35 the lamp and its circuit arrangements; Fig. 4 is a partial elevation with parts broken away and in section showing a modified form of electrode construction; and Fig. 5 is a perspective view of a detail.

40 In the drawings, 1 represents a central draft tube or chimney forming the back-bone of the lamp proper. Ordinarily the chimney or draft tube is formed in three sections, one above the hood 2 of the lamp, one between 45 the hood 2 and the platform or partition 3, and a third section below the platform 3. The electrode-feeding mechanism of the lamp proper is located between the hood 2 and platform 3.

50 A pair of similar solenoid coils 4 are arranged side by side and secured to the middle section of the chimney member 1. The legs of a U-shaped armature 5 project into the coils 4. The movable member 6 of a dash- 55 pot is secured to the under side of the yoke

of the armature 5 by a connecting portion or stem 7. The stationary member 8 of the dash-pot is secured to the platform 3. A connecting rod 9 has its upper end secured to but insulated from the armature 5. The 60 lower end of the connecting rod 9, which is preferably curved as shown in Figs. 1 and 4, is secured to the yoke of U-shaped member 10. The ends of the legs of the U-shaped member 10 are pivotally connected to the 65 ends of a U-shaped member 11 which is pivotally connected at diametrically-opposed points to the lower end or section of the chimney member 1 by means of pintles or trunnions 11' carried by the chimney member. The yoke portion of the member 11 is secured to one end of an arc-shaped bar advantageously made out of some metal such as wrought copper. This bar forms the 70 starting portion of the positive electrode.

When the member 11 is oscillated about its pivotal point of support by the reciprocation of the armature 5, the member 12, which in the position shown in Fig. 1 of the drawings has its lower end substantially flush with 80 the right-hand wall of the chimney 1, passes through the lower end of the chimney through slots 13 and 14 (see Fig. 4) formed in the right end and left-hand side of the member 1. In the construction shown the 85 bar 12 is curved about its pivotal point of support as a center and passes through the center of the chimney member when oscillated.

In the lamp shown in Fig. 1, the main or 90 working portion of the positive electrode of the lamp is in the form of a curved bar 15 of metal, such as wrought copper, rectangular and considerably larger in cross-section than the starting portion 12. The bar 15 is carried by a U-shaped member 16 to the yoke portion of which it is secured in any suitable manner as by means of screws or bolts 17. The member 16 is pivotally secured to the member 1 at the same diametrically opposed points at which the member 11 is pivoted. The members 11 and 16 may be mounted on the same trunnions 11' carried by the member 1. As shown, the ends of the legs of the member 16 are connected together by a member 19.

When the parts are in the position shown in Fig. 1, gravity holds the electrode portion 15 in the position in which it projects through the left-hand side of the wall member 1 as 110

seen in Fig. 1 to a point near the opposite side of the wall. A shield or guard 20 which is apertured to receive the bar 15 is carried by it in such position that it then fits against the outer side of the member 1 and with the bar 15 effectually closes the slot 14 in the lower end of the member 1. The guard 20, which may advantageously be formed out of sheet metal, is provided with an off-set portion 21 which is slotted to receive one of the screws 17 by which it is adjustably secured to the bar 15. In the position shown in Fig. 1 there is a space between the adjacent ends of the bars or portion 12 and 15. When the member 12 is rocked about its pivotal point of support its lower end engages the adjacent end of the bar 15 and carries it out of the draft tube 1.

The construction shown in Fig. 4 is identical with that shown in Fig. 1 with the exception that the bar or portion 15 of Fig. 1, which is substantially rectangular in cross-section, is replaced by a bar or portion 15 which is circular in cross-section. The position of the parts in Fig. 4 is that in which the starting portion of the positive electrode holds the working portion of the electrode out of the chimney 1.

The lower consuming electrode 25 of the lamp, which is preferably formed of or contains some material such as magnetite, rutile, titanium carbide, etc., giving a flaming or luminous arc, is movably held in line with the axis of the chimney 1 by an arm or bracket 26 carried by the lower end of a tubular member 27 which slides in a tube or guide 28 supported from the frame work of the lamp. The yoke of a clutch member 29 surrounds the member 27. To the yoke member of the clutch 29 is secured one end of a pawl 30. The other end of the pawl 30 is formed with a passage in it through which extends the stem 7 connecting the magnet 5 with the movable member 6 of the dash-pot. Below the yoke member of the clutch 29 is located the yoke member of the clutch 31. This yoke member also surrounds the member 27. A spring 33 normally holds the pawl member 32 in the position in which the member 27 is locked between it and its coöperating yoke. Stops 34 and 35, one at least of which is preferably adjustable, limit the movement of the clutch 31.

When the armature 5 is raised as by the energization of the coils 4, its upward movement causes a corresponding movement of the adjacent end of the pawl 30. As the outer end of the pawl 30 is raised the member 27 is locked between it and its coöperating yoke member, after which further upward movement of the armature causes a corresponding upward movement of the electrode 25. The upward movement of the member 27 will cause a corresponding movement of the clutch 31 until the pawl 32 engages the upper stop 34 after which further movement

of the member 27 will take place without corresponding movement of the clutch 31. When the armature 5 is subsequently lowered, the member 27 will drop back until its downward movement is arrested by the engagement of the pawl 32 by the lower stop 35. When this occurs, the yoke member of the clutch 29 drops down into engagement with the yoke of the clutch 31 as shown in Fig. 3.

A series coil 36 and a voltage coil 37 are secured to the frame-work of the lamp with their axes in alinement. The series coil 36, which is of the iron-clad solenoid type, is provided with a U-shaped piece of magnetic material 38, the legs of which extend parallel to the axis of the coil. A cylindrical member 39 of magnetic material has its upper end secured to the yoke of the U-shaped member 38. The lower end of the member 39 projects into the coil 36 which is tubular and holds the member 38 in place. The movable armature coöperating with the coil 36 comprises a core 40 of magnetic material which enters the bore of coil 36 and has secured to its lower end a disk 41 of magnetic material. To the under side of the disk 41 is secured a socket member 42 by means of screws 43. As is clearly seen in the construction the socket member 42 is insulated from the disk 41. A contact member 44, which may be advantageously formed of some material such as copper, is held by the socket member 42. The voltage coil 37, which is also of the solenoid iron-clad type, is provided with a U-shaped piece of magnetic material 45 the legs of which extend parallel to the axis of the core. A tubular member 46 which enters the upper end of the coil 37 and passes through an opening in the member 45 serves to secure the latter in place. The armature coöperating with the coil 37 comprises a tubular body of magnetic material 47 which carries at its lower end a disk 48 of magnetic material. The lower end of the member 47 is interiorly threaded to engage the threaded portion of a tube or rod 49. By rotating the member 47 relative to the rod 49 the relative longitudinal position of the member and rod may be adjusted. A lock nut 50 serves as a means for locking the member 47 against accidental displacement. The upper end of the rod 49 is secured to a cross-head or member 52 preferably formed of non-magnetic material. A socket member 53 secured to but insulated from the upper side of the member 52 supports a cylindrical contact member 54 which may be advantageously formed out of carbon.

The contact members 44 and 54 are in alinement with each other and in the position shown in Fig. 2 when the coils 36 and 37 are both deenergized the contact members engage each other. When the coil 36 is energized the contact 44 will be moved out of en-

gagement with the contact 54. When there-
after the coil 36 is deenergized or the coil 37
is operatively energized, the downward
movement of the contact 44 on the one hand
5 or the upward movement of the contact 54
on the other hand will again bring the con-
tacts into engagement. The lower section of
the draft tube or chimney is preferably insu-
lated from the upper section of the chimney
10 and from the platform 3 and is electrically
connected to the two parts 12 and 15 of the
positive electrode by flexible conductors 56
and 57. A resistance conductor 58 is mount-
ed on a suitable spool or support 59 carried
15 by the platform 3. A reflector 60 is secured
against the lower end of the chimney in any
suitable manner.

The circuit arrangements of the lamp are
shown in diagram in Fig. 3 where 62 and 63
20 represent the positive and negative terminals
of the lamp respectively. One terminal of
the coil 36 is connected to the terminal 62.
The other terminal of the coil 36 is shown in
the diagram as connected by a conductor 64
25 to the copper bars 12 and 15 forming the
upper and positive electrode of the lamp.

The conductor 65 connects the negative
terminal of the lamp with the negative elec-
trode 25. One terminal of the coils 4, which
30 are in series with each other, is connected to
the negative terminal 63 of the lamp. The
other terminal of the coils 4 is connected to
the contact 44 by a conductor 66. One ter-
minal of the coil 34 is connected to the con-
35 ductor 66 at the point 67. The other termi-
nal of the coil 37 is connected to the lamp
terminal 62 through a conductor 68 and a
resistance conductor 58. The contact 54 is
connected to the conductor 68 at the point 71.

40 The normal running position of the lamp
is that shown in Figs. 1 and 3. When the
lamp is out of service the only change in
position of parts is due to the dropping of
the contact 44 into engagement with contact
45 54. When the lamp is put into service cur-
rent begins to flow between the terminals 62
and 63 through the resistance conductor 58,
contacts 44 and 54 which will then be in en-
gagement, conductor 66 and coils 4. This
50 will operatively energize the coils 4 and cause
the armature 5 to be raised, rocking the up-
per electrode from the position shown in
Figs. 1 and 3 to that shown in Fig. 4, and at
the same time moving the lower electrode 25
55 into engagement with the under side of the
bar 12. As soon as this occurs current will
begin to flow between the electrodes through
a circuit including the winding of the coil 36,
conductors 64, and conductor 65. The pas-
60 sage of this current will energize the coil 36
and cause its coöperating armature to break
the engagement between contacts 44 and 54.

When engagement between contacts 44
65 and 54 is broken the coils 4 are no longer
operatively energized and the armature 5

and member 27 begin to move downward.
The downward movement of the parts will be
delayed by the action of the dash-pot which
is arranged to prevent a rapid downward
movement of the parts, while allowing rapid
upward movement thereof. As the member
70 27 and electrode 25 move downward, an arc
is drawn between the bar 12 and the elec-
trode 25. The upper end of this arc will be
transferred from the bar 12 to the working
75 portion of the electrode as the latter moves
into the lower end of the member 1. The
downward movement of the electrode 25 and
consequently the length of the arc is limited
by the engagement of the pawl 32 with the
stop 35. The arc thus started is maintained
80 under ordinary conditions until from an in-
crease in its length or from other causes its
voltage rises beyond a predetermined amount
whereupon the passage of current through
the voltage coil 37 will be sufficient to oper-
atively energize it and raise the contact 54
85 into engagement with the contact 44. When
this occurs the coils 4 will again be oper-
atively energized and the electrode 25 will be
90 again moved into engagement with the start-
ing portion 12 of the upper electrode. This
feeding operation of the lamp will be re-
peated as often as conditions of service re-
quire it.

95 The particular lamp hereinbefore described
and illustrated is intended for operation in a
series circuit though it can readily be adapted
for use in a constant potential circuit. When
used as a series lamp the contacts 44 and 54
100 serve as the automatic cut-out of the lamp.
It will of course be understood that in case
the lamp fails to operate properly and to
maintain an arc, the contact 44 will remain in
engagement with the contact 54. The only
105 windings of the lamp which will then be in
circuit will be resistance conductor 58, con-
ductor 71, contacts 44 and 54, conductor 66
and coils 4. As the latter coils can advan-
tageously be made with low resistance this
110 arrangement forms an efficient cut-out for
the lamp. By making the contact 44 con-
nected to the negative side of the lamp of
copper and the coöperating contact 54 of
carbon, good electrical connection between
115 the contacts is obtained when the contacts
engage while arcing between the contacts
when they separate is reduced to a minimum.

The resistance of the coil 37 is great enough
so that the current passing through it and
120 the coils 4 between the lamp terminals 62
and 63 when the arc is burning is insufficient
to operatively energize the coils 4. The ar-
rangement of the coils 36 and 37 and the con-
tacts controlled by them is simple, compact,
125 and reliable.

130 The upper electrode disclosed by the appli-
cation is very satisfactory. Both the start-
ing portion and the working portion of each
electrode are readily replaceable when by

reason of long continued use or other causes replacement is desirable. It will be understood, however, that the positive electrode of this lamp is practically non-consuming; 5 that is, no consumption of this electrode is necessary in order to maintain the arc. The only consumption of the upper electrode which occurs is incidental and is usually due to a comparatively slow oxidation produced 10 by the heat of the arc.

The parts are so proportioned that the positive electrode allows the proper flow of air through the draft tube or chimney to steady the arc and to carry the arc products out of 15 the lamp. The parts of the upper electrode 12 and 15 may both be moved out of the chimney to allow of cleaning the latter. The use of a movable positive electrode insures that in starting an arc the lower electrode 20 engages a clean portion of the upper electrode thus establishing a good electrical connection between the electrodes. The sheet metal shield 20 can be readily secured to or removed from the working portion of the 25 electrode and with the working portion of the electrode effectually closes the large aperture 14 in the chimney thus improving the draft arrangement, and by giving the proper direction to the air currents increasing the 30 stability of the arc.

While we have hereinbefore described and illustrated the best form of our invention now known to us it will be readily understood by all those skilled in the art that 35 changes may be made in the embodiments disclosed without departing from the spirit of our invention.

What we claim as new and desire to secure by Letters Patent of the United States, is, 40 1. In an arc lamp, a draft tube having an opening formed in it, an electrode comprising a metallic bar movable through said opening, a shield or guard carried by said bar and arranged to engage the side of said draft tube 45 to limit the movement of the bar in one direction relative to said tube and to assist in closing said opening, and means for adjustably securing said shield to said bar.

2. In an arc lamp, a coil in series with the 50 arc and a voltage coil shunting the arc and the series coil placed end to end and in alignment with each other, a movable armature entering said series coil, a contact carried thereby, and a movable armature entering 55 said voltage coil and contact carried thereby, said contacts being in engagement with each other when both coils are deenergized, out of engagement with each other when the series coil is operatively energized and in engagement with each other when both coils are 60 operatively energized.

3. In an arc lamp, an electrode-feeding magnet and a pair of coöperative contacts controlling the energization thereof, a coil in

series with the arc for moving one of said contacts to deenergize the feeding magnet, and a voltage coil shunting the arc and the series coil to move the other of said contacts to energize said feeding magnet on a predetermined rise in voltage of the arc. 65

4. In an arc lamp, a draft tube having an opening formed in it, electrodes each comprising a metallic bar movable in or through said opening, and a shield or guard detachably secured to said bar and arranged to engage the 70 side of said draft tube to limit the movement of the bar in one direction relative to said tube and to assist in closing said opening.

5. In an arc lamp, a draft tube having an opening formed in it, an electrode comprising 80 a metallic bar movable through said opening, and a shield or guard carried by said bar and arranged to engage the side of said draft tube to limit the movement of the bar in one direction relative to said tube and to assist in 85 closing said opening, said guard or shield being formed of sheet metal.

6. In an arc lamp, a draft tube having an opening formed in it, an electrode comprising a member movable through said opening, 90 and a shield or guard carried by said bar and arranged to engage the side of said draft tube to limit the movement of the bar in one direction relative to said tube and to assist in closing said opening, said guard or shield 95 being formed of a metal plate provided with an aperture through which the member passes.

7. In an arc lamp, an electrode-feeding magnet and a pair of contacts arranged in the 100 circuit of said magnet, a coil in series with the arc for moving one of said contacts to deenergize the feeding-magnet, and a voltage coil shunting the arc and the series coil to move the other of said contacts to energize 105 the said feeding-magnet on a predetermined rise in voltage of the arc.

8. In an arc lamp, a coil in series with the arc and a voltage coil shunting the arc and the series coil placed one above the other, 110 armature members associated with said coils, and contacts carried by said armature members, the parts being so proportioned and arranged that said contacts are in engagement with each other when both coils are 115 deenergized, out of engagement with each other when the series coil is operatively energized, and in engagement with each other when both coils are operatively energized.

In witness whereof, we have hereunto set 120 our hands this twenty-eighth day of April, 1905.

RICHARD FLEMING.
